UNITED STATES PATENT OFFICE.

JAMES DENNY DAUGHERTY, OF KITTANNING, PENNSYLVANIA, ASSIGNEE TO ELLIOTT-FISHER COMPANY, OF NEW YORK, N. Y., A CORPORATION OF DELAWARE.

COMPUTING-MACHINE.

1,199,248.

Specification of Letters Patent. Patented Sept. 26, 1916.

Application filed May 10, 1901. Serial No. 59,631.

To all whom it may concern:

Be it known that I, JAMES D. DAUGHERTY, a citizen of the United States, residing at Kittanning, in the county of Armstrong and State of Pennsylvania, have invented new and useful Improvements in Computing-Machines, of which the following is a specification.

This invention relates to calculating machines, but more particularly to a combined typewriting and adding machine of that general type disclosed in Patent No. 517,735, issued to me April 3, 1894.

In the patented construction a typewriter of the round platen or traveling paper carriage type is equipped with computing mechanism including a series of denominational members, digit carriers, or wheels and operating mechanism therefor. The operating mechanism includes a master wheel or actuator to which variable or differential rotary movement is transmitted from the numeral keys of the typewriter, for the purpose of effecting corresponding movements of those 25 digit carriers whose denominational positions correspond with the denominational positions or orders in which the digits are printed in the column to be computed. The digit carriers are mounted in a movable 30 frame or computing carriage which is advanced relative to the actuator by the typewriter carriage, through the medium of interposed mechanism so arranged that the computing device may be rendered operative at various points in the travel of the carriage, according to the location of the column upon the work sheet. This patented construction, while efficient, imposes upon the keys the burden not only of controlling the operation of the computing device, but also of actually transmitting motion thereto, the power necessary for the operation of both the printing and computing mechanism being derived from the finger of the operator. Furthermore, even when the computing mechanism proper is not operated by the actuator, the keys are nevertheless burdened by the actuator and its operating connections when the said keys are depressed for the purpose of printing digits which are not to be included in the computation.

Having in mind these more or less objectionable characteristics of my former construction, my present invention is directed to the provision of means whereby the nu-

meral keys of the typewriter, while constituting means for causing or controlling the operation of the computing device, will, nevertheless, be relieved of the burden of directly operating or transmitting movement to either the computing device proper or the actuating mechanism therefor. This end is attained by providing a motor constantly tending to rotate the actuator, but normally restrained by key operated mechanism interposed between the keys and the actuator and automatically connected to the keys by the movement of the carriage, so that, during a given period of the carriage travel, the keys may be operated to release the actuator which will be driven by the motor and arrested by a variable or differential stop mechanism after the actuator has moved a distance corresponding to the value of the particular numeral key depressed. The present invention is also directed to the provision of means for normally relieving the keys of the burden incidental to the actuation of the connections between the keys and the actuator, this end being attained by providing means for automatically moving an element of said connection to an inoperative position to permit the keys to be operated independently of the actuator or its connections when the printing point of the typewriter is located outside of or beyond the column to be added.

Another object of the invention is to automatically restore the power expended by the motor, after each operation of the computing device incidental to the printing of a number in the column to be computed. This end is attained by providing the motor with a restoring arm which advances toward the left a distance proportionate to the power expended by the motor and which is located in the path of the typewriter carriage when the latter is retracted, so that, upon the retraction of the carriage to begin a new line of writing, the motor restoring arm will be automatically moved back to its normal position, thus re-winding the motor to restore the energy expended.

Further objects are to provide improved mechanism for automatically causing relative movement of the computing device and its actuator at the proper point in the travel of the carriage, for the purpose of presenting the proper denominational members or digit carriers in operative position.

Other objects of the invention, and further structural characteristics of the preferred embodiment thereof, will appear during the course of the succeeding description 5 of the construction illustrated in the accompanying drawings and embraced within the scope of the appended claims.

In said drawings:—Figure 1 is a plan view of my combined typewriting and adding machine, the computing carriage and the motor arm being shown in the advanced positions assumed by them after the printing 10 of a number in the column to be computed and parts of the typewriter structure being broken away to facilitate the illustration. Fig. 2 is a similar view illustrating the manner in which the retraction of the computing carriage and the motor arm is effected by the retraction of the typewriter carriage. Fig. 3 is a sectional front elevation of the machine, showing the relative arrangement 15 of the escapements and key levers. Fig. 4 is a side elevation of the machine with the right hand end of the computing device casing and also the right hand end of the computing carriage broken away. Fig. 5 is a vertical sectional view on a somewhat enlarged scale designed more particularly to show the relation of one of the escapement 20 devices and the controlling lever 67 to the mechanism of the typewriter. Fig. 5^a is a sectional elevation showing a modified arrangement of escapement in which the stop arm is mounted independently of, but operated by the key lever. Fig. 6 is a detail 25 perspective view showing the normal positions of a key, an escapement, and the locking arm for the master wheel. Fig. 7 is a similar view showing the positions assumed 30 by the same parts when the key is depressed. Figs. 8, 9, and 10 are detail perspective views designed to show the action of an escapement and the master wheel locking arm, Fig. 8 showing the normal position of the 35 parts, Fig. 9 the positions assumed by the escapement stop arm and the locking arm upon the depression of a key and the manner in which the rotary movement of the master wheel is limited by the stop 57 and 40 the coöperating collar 53, and Fig. 10 showing how, upon the rising of the key, the locking arm locks the master wheel and the stop arm of the escapement releases the escapement wheel and permits the independent 45 forward rotation of the latter. Fig. 11 is a front elevation of the motor, showing in dotted lines a position which may be assumed by the restoring arm after the motor has been utilized to operate the computing 50 mechanism. Fig. 12 is a similar view illustrating the manner in which the restoring arm is retracted or restored to normal position by the retraction of the typewriter carriage. Fig. 13 is a sectional view of the 55 motor. Fig. 14 is a detail perspective view

of a portion of the bail which is rocked by the key levers to unlock the master wheel, the normal positions of the swinging arms and the controlling lever and trip being shown in full lines, and the positions assumed by these parts when the controlling lever has been operated by the trip being indicated in dotted lines. Fig. 15 is a similar view indicating the manner in which the trip mounted on the typewriter carriage restores the controlling lever and the swinging arms of the bail to their normal positions as the typewriter carriage is retracted. Fig. 16 is a detail view of the detent for retaining the rock shaft 50 in either position. Fig. 17 is a horizontal section through the computing device casing, showing in plan the mechanism contained therein. Fig. 18 is a perspective view of one of the number wheels, the trip levers carried thereby and the cam disk coöperating with the trip levers. Fig. 19 is an elevation of the mechanism for locking and releasing the master wheel, the depressed position of the key and the released position of the master-wheel lock being indicated in dotted lines. Fig. 20 is a sectional view of a portion of the computing mechanism. Fig. 21 is a sectional view of the computing device casing disclosing the interior mechanism, the number 90 wheel resetting lever and associated parts being moved to the positions they assume at the completion of the number wheel resetting operation. Fig. 22 is a detail perspective view of the resetting member, and Fig. 100 95 23 is a similar view of the locking wheel.

For the purpose of this disclosure, I have shown an Underwood typewriter equipped in accordance with my invention, but it should be distinctly understood at the outset that in certain of its broader aspects, my invention relates to calculating machines, regardless of whether or not recording or printing mechanism is employed in connection therewith. In certain other aspects, the invention relates to new and useful features of a combined recording and calculating mechanism, and, in a more restricted sense, it relates to a combined typewriting and computing mechanism the novelty and utility of which is not dependent upon the particular type or class of typewriter employed, since the generic invention involved is applicable to a machine including as an adjunctive organization thereof any recording mechanism having the essential characteristics of all typewriters, to-wit, printing mechanism and paper supporting means which are relatively movable, one with respect to the other to effect the spacing of the 110 characters printed.

The general organization of the machine.

By way of premise, the general organization of the machine will be described in 120 130

brief. To one side of the frame of an Underwood typewriter, which is of the round platen front strike type, is attached a small casing inclosing the computing device proper, which embraces a computing carriage containing a series of nine number wheels which are successively presented in mesh with a master wheel by the movement of the computing carriage. Normally, this computing carriage remains stationary, the master wheel is held locked against rotary movement, and the key levers of the typewriter are entirely disconnected from the operating connections of the computing mechanism, so that the typewriter may be used independently in the ordinary manner. Therefore, in the writing of any desired matter, as for instance, descriptions of the items of a bill, the typewriter is unaffected by the presence of the computing mechanism and the keys are not burdened by the operating connections thereof. By means, however, of adjustable devices mounted on the typewriter carriage, the computing mechanism is brought under the control of the numeral keys of the typewriter whenever, in the travel of the platen, that space, appropriated on the work sheet to the column of numbers to be computed, is brought opposite the printing point of the machine. These devices, acting automatically at the proper time, establish first, a coöperative relation between the keys and a series of stop devices and also between the keys and the locking mechanism of the master wheel, and second, a coöperative relation between the carriage of the typewriter and the computing carriage. When this coöperative relation of the parts has been automatically effected, the depression of a key will effect the printing of a digit and the release of the master wheel. When so released, the master wheel will be rotated by a motor until arrested by the particular stop device appropriated to and coöperating with the key depressed. This movement of the master wheel will be proportionate to the value of the digit printed and the same proportionate rotary movement will be transmitted, by the master wheel, to the number wheel occupying that denominational position in the series of number wheels, which corresponds to the denominational position of the printed digit in the column to be computed. When the key is released, the master wheel will be automatically locked against further rotary movement, and as the typewriter carriage advances to present the next order of denomination of the column opposite the printing point, the computing carriage will be simultaneously moved to present the next or corresponding number wheel in mesh with the master wheel, and this cycle of operations will be repeated as often as digits are printed in the column.

When the carriage is retracted it automatically destroys the coöperative relation between the keys and the master wheel, re-winds the driving motor for said wheel, and restores the computing carriage to its normal position. 70

Associated with the number wheels is carrying mechanism of any approved form for transferring to a wheel of higher denomination the amount accumulated upon any wheel, when the latter reaches the limit of its denominational capacity the carrying mechanism illustrated in the drawings being that disclosed in Reissue Patent #11147 to A. C. Ludlum. The number wheels are restored to zero by the manual rotation of the number wheel shaft, which is equipped with devices for engaging and rotating the number wheels. 75 80 85

The machine in detail.

85

1 indicates the frame of an Underwood typewriter, 2 the traveling carriage thereof, which is power driven and escapement controlled, as usual, 3 the numeral keys, 4 the numeral key levers, and 5 the letter key levers. As is well understood in the art, the operation of any key lever effects the printing of the proper character and also operates the escapement of the typewriter to permit sufficient advance of the carriage to space the characters printed. 90 95

In accordance with my invention, the computing device casing 6 is suitably attached to the right hand side of the typewriter frame and incloses the computing device proper. This computing device includes a series of nine denominational members, number wheels, or digit carriers, *a*, *b*, *c*, *d*, *e*, *f*, *g*, *h* and *i*, which may represent any desired denominational values, as for instance, units, tens, hundreds, thousands, tens of thousands, hundreds of thousands, millions, tens of millions, and hundreds of millions; or, if money values are computed, the two wheels of lowest denomination may indicate units and tens of cents. 100 105 110 115

The computing carriage.—The number wheels are loosely mounted on a number wheel shaft 7 extending across the computing carriage 8 movably mounted upon rods or tracks 9 and 10 extending across the casing 6 directly under a pair of bars 11 and 12 which rest upon antifrictional elements, as for instance, balls 13, interposed between the bars and tracks, as shown in Fig. 21, and serving to render the movement of the computing carriage substantially antifrictional. Each number wheel in the present embodiment of the invention is provided with 125 thirty teeth, bearing three series of digits each ranging from "0" to "9" inclusive, one digit on each wheel being exhibited opposite a sight opening 14 in the casing 6, as shown in Fig. 1. The several number 130

wheels *a*, *b*, etc., are designed to be presented successively in coöperative relation with an actuator or master wheel 15 during the movement of the computing carriage upon the tracks 9 and 10, said carriage being normally located at the extreme right hand side of the casing 6 so that the number wheel *i* of highest order will be to the right of and out of engagement with the actuator 15, as shown in Fig. 20.

The variable advancing and retracting mechanism for the computing carriage.—The advance of the computing carriage to present the number wheel of highest order, and thereafter successive number wheels, opposite the master wheel or actuator 15, is effected by the propelling mechanism of the typewriter carriage 16 through the medium of the latter. It is contemplated, however, to provide means whereby this movement of the two carriages 8 and 16 in unison will be occasioned only during that period in the travel of the typewriter carriage during which the printing point of the machine will be opposite the column to be computed, so that, during the printing of characters outside of the limits of such column, the computing carriage will remain in its normal position. It will, of course, be understood that the location, on the work sheet, of the column to be computed will vary, although it is usually adjacent to the right hand edge of the paper. Therefore, the present machine embodies mechanism variable in accordance with the location of the column on the work sheet and arranged to automatically connect the typewriter carriage with the computing carriage at the proper point in the travel of the former and to maintain such connection while the printing mechanism is opposite the column to be computed, thus insuring, by the uniform movement of the two carriages, the location of the actuator opposite the number wheel of that denomination which corresponds with the denominational position of the printing mechanism with respect to the column. This variable carriage connecting mechanism includes a vertically disposed rock shaft 17 mounted in suitable bearings adjacent to the rear side of the typewriter and provided at its lower end with a forwardly extending arm 18 having a vertically disposed extremity 19 connected by a link 20 to the computing carriage 8, as shown in Figs. 1, 3 and 4. At the upper end of the shaft 17 is a forwardly extending arm 21 having a vertically disposed extremity 22 arranged in the path of two projections, blocks or trips 23 and 24 adjustably mounted in any suitable manner on the typewriter carriage, as for instance, upon a rod 25 extending longitudinally of the carriage and movable therewith. Any suitable means, as for instance, set screws 26, may be provided to retain the

blocks 23 and 24 in their adjusted positions upon the rod 25.

As the typewriter carriage moves to the left during the operation of printing, the computing carriage 8 will remain in its normal inoperative position at the right hand side of the casing 6. But, just before this movement of the typewriter carriage brings the printing point of the machine opposite the column to be computed, the block or trip 23 having been advanced by the typewriter carriage into engagement with the arm 21, will establish an operative connection between the typewriter and computing carriages. Therefore, as the typewriter carriage advances into position for the printing of a digit in the highest denominational position in the column to be computed, the computing carriage will be simultaneously moved to the left to present the first number wheel *i* in coöperative relation with the master wheel or actuator 15. This connection between the carriages continues during the printing of a number in the column, so that, as each digit is printed in a given denominational position in the column, the master wheel will be in coöperative relation with the number wheel of corresponding denomination. It will therefore be seen that if the depression of the numeral keys to print digits in the column, causes rotary movement of the master wheel corresponding in extent to the values of the digits printed, the number wheels of the computing device, corresponding in denominational position to the denominational positions of the digits printed, will be operated to an extent corresponding to the unitary values of such digits and, that the values printed will thus be accumulated upon the computing device.

By adjusting the trip 23 to various positions on the bar 25, the computing device may be rendered operative at various points in the travel of the carriage, in accordance with the varying location on the work sheet of the column to be computed. Ordinarily, however, in making out bills, or the like, the major portion of the carriage travel is devoted to the writing of items or other matter beginning at the left hand margin of the work sheet, and the computing device is rendered operative when the carriage is in position to permit the printing of a column of digits or numbers adjacent to the right hand margin of the sheet. When the typewriter carriage is retracted, the trip or block 24 will engage the arm 21, thus swinging the latter back to effect the retraction of the computing device carriage to its normal inoperative position, see Fig. 2.

We have now seen how the computing device proper is mounted in a small casing at the right of the typewriter, and how, by means of variable connecting mechanism,

the carriage propelling mechanism of the typewriter serves to automatically render the computing device operative at a predetermined point in the travel of the carriage, 5 and how, after the printing of a number, the computing device is automatically rendered inoperative upon the retraction of the carriage, so that, when digits are printed outside of the column to be computed, no 10 corresponding operation of the computing device will be effected.

The motor for driving the master wheel.—It is next in order to describe the mechanism whereby, when a numeral key of the 15 typewriter is depressed, to effect the printing of a digit in the column to be computed, the master wheel will be operated to rotate the proper number wheel for the purpose of including the value of the printed 20 digit in the computation to be effected by the computing device.

As previously stated, one of the primary objects of the invention is to lighten the touch by relieving the keys of the burden 25 usually imposed upon them. This is accomplished by providing power mechanism for driving the master wheel and controlling mechanism by means of which the operations of the master wheel are controlled 30 from the keys, said keys and master wheel being operatively connected in the sense that the depression of the keys causes the operation of the master wheel, although they do not actually transmit movement to 35 the latter from the finger of the operator.

As shown in Figs. 3 and 4, the master wheel or actuator 15 is keyed or otherwise fixed upon an actuator shaft 27 journaled in suitable bearings and extending through 40 the casing 6 and across the frame of the typewriter above the key levers. This shaft 27 is driven by a motor 28 comprising a motor spring 29 fixed at one end, as indicated at 30, to a fixed part, as for instance, 45 one of two motor supporting brackets 31 and 32. The opposite or inner end of the spring 29 is secured, as indicated at 33, to the hub 34 of a spring drum 35 inclosing the spring 29 and fixed upon the motor shaft 36 journaled in suitable bearings in the brackets 31 and 32, see Figs. 4 and 13. Also fixed upon the shaft 36, in spaced relation to the drum 35, is a motor ratchet 37 designed to drive a comparatively large 55 beveled motor gear 38 through the medium of a pawl 39 mounted on the front face of the gear 38 and urged into engagement with a tooth of the ratchet 37 by a spring 40, see Fig. 12. When unrestrained, the spring 29 60 rotates the motor shaft 36 in the direction of the arrow in Fig. 11, and thus causes the ratchet wheel 37 to drive the motor gear 38 through the medium of the interposed pawl 39. The movement of the motor gear 38 is 65 transmitted to the actuator shaft 27 through

the medium of a train of speed gearing including a gear 41 and a pinion 42, Figs. 3 and 4.

The rewinding or restoring means for the motor.—It is contemplated to automatically 70 restore the energy expended by the motor after each number has been cumulated upon the computing device or register. In the present embodiment of the invention this end is attained by extending a motor re- 75 setting or restoring arm 43 from the drum 35 into the path of a projecting portion 44 of the typewriter carriage, see Figs. 2, 4 and 12. As the operation of printing progresses, the typewriter carriage moves toward the left and away from the arm 43, and, as the motor operates to transmit motion to the master wheel during the printing and recording or registering of a number, the upper end of the motor restoring 80 arm 43 will advance toward the left a distance proportionate to the rotation of the motor gear 38 under the impulse of the spring 29. As the carriage is retracted, 85 however, after the recording and registering of a number, the projection 44 will engage the arm 43 and thus return the latter to its normal position, the motor gear 38 being held stationary, by mechanism to be described, during the return of the arm 43, 90 and the motor ratchet 37 clicking idly past the pawl 39 as the motor shaft rotates in the direction of the arrow in Fig. 12 to rewind 95 the motor spring.

The key operated controlling means for the master wheel.—While the motor 28 constantly exerts a force tending to rotate the actuator shaft and actuator, it is normally restrained by a locking arm 45, see Figs. 4, 100 6, 7 and 19, fixed to and extending upwardly from a shaft 46 and having a beak or projection 47 which normally extends between two teeth of the master wheel 15 and locks the same against rotary movement. The shaft 46 extends transversely 105 across the frames 1 and 6 and is designed to be rocked for the purpose of moving the arm 45 out of engagement with the actuator 15 and thus releasing the latter upon the depression of a numeral key of the typewriter. To accomplish this result, the shaft 46 is provided with a rearwardly extending bail 48, see Figs. 6 and 7, comprising arms 49 and a rock shaft 50 provided with a series of radially disposed arms 51. 110 These arms 51 are located directly below the numeral key levers 4 and are disposed vertically during the printing of a number in the column to be computed. These arms or projections 51 serve to establish an operative 115 relation between the bail 48 and the numeral key levers, while permitting said bail to occupy a position sufficiently depressed to prevent its actuation when one of the levers 5 are operated upon the depression of a 120

letter key of the typewriter. When a numeral key is depressed to print a numeral in the column to be computed, the lever of said key, by engagement with one of the arms 51, depresses the bail 48 and thus rocks the shaft 46 to withdraw the locking arm 45 from engagement with the actuator and said actuator will immediately rotate under the impulse of the motor a distance proportionate to the value of the particular key depressed. This brings us to a consideration of the mechanism employed for determining or controlling the degree of movement of the actuator.

15 *The controlling escapements for the master wheel.*—This mechanism embraces a series of escapements each appropriated to a numeral key and having a throw proportionate to the value thereof. Each escapement includes an escapement wheel 52 loosely mounted on the actuator shaft 27 adjacent to one end of a stop collar 53 fixed on the shaft and provided with a recess 54 the end walls of which constitute spaced stops 55 and 56 secured to and movable with the actuator shaft. Between these two stops 55 and 56 on the shaft extends an intermediate stop 57, projecting from the side face of the escapement wheel 52. Normally, 20 the intermediate stop 57 is retained in engagement with the advanced stop 56 by a spiral spring 58 encircling the collar and having its opposite ends fixed to the collar 53 and the wheel 52, respectively. (Fig. 3). 25 It is obvious that, as the wheel 52 is loose on the shaft 27, the tendency of the spring 58 to unwind will throw the wheel 52 around until this movement, independent of the shaft 27, is arrested by the engagement 30 of the intermediate stop 57, carried by the wheel, with the advanced stop 56, carried by the shaft.

Operated by, and preferably secured to the adjacent numeral key lever 4 is an escapement-wheel locking member 59 having a beak 60, see Fig. 6, which, when the numeral key is depressed, is brought into engagement with one of the teeth of the escapement wheel 52, see Fig. 7, to lock the same against 40 rotary movement. We have already seen that this same movement of the key lever which causes the locking of the escapement wheel 52 by the locking member 59, effects the release of the master wheel or actuator 15 45 through the medium of the bail 48, the shaft 46, and the arm 45, but by noting the normal relation of the beak 60 to the adjacent escapement wheel and the extent of the engagement between the beak 47 and the actuator 15, Fig. 6, it will be evident that, as the numeral key is depressed, the escapement wheel will be locked by the arm 59 before the actuator is released by the arm 45. Therefore, as soon as the depression of the key lever effects the release of the master wheel 15

by the withdrawal of the arm 45 therefrom, the motor will rotate the shaft 27 in the direction of the arrow in Fig. 8, and this movement will continue until arrested by the engagement of the stop 55 on the shaft 70 with the now stationary stop 57 on the locked escapement wheel, see Fig. 9. Thus it will be seen that since the stops 56 and 57 are normally in engagement, Fig. 8, and as the stops 55 and 57 are in engagement when 75 the movement is completed, Fig. 9, the extent or degree of the movement will be determined by the distance between the stops 55 and 56 on the actuator shaft. Therefore, the recess 54 in each of the collars 53 is of a 80 different length, the distance between the stops formed by the end walls of the recess being proportionate to the value of the particular numeral key to which the escapement is appropriated. When the key has been 85 depressed to print a digit and the actuator has been released and operated in the manner described, to turn a number wheel of the computing device a number of increments or units of movement corresponding to the 90 value of such digit, the key is released, thus withdrawing the locking member 59 from engagement with the escapement wheel 52 and permitting a spring 61 acting on the 95 bail 48 to move the arm 45 into locking engagement with the actuator 15. It will be noted, however, that the actuator 15 is locked before the escapement wheel is released, this being due to the same relation 100 of parts which causes the locking of the escapement wheel before the actuator is released in the manner heretofore explained.

As the locking member 59 moves out of engagement with the escapement wheel, the spring 58 will advance the latter until its 105 stop 57 engages the advanced stop 56 on the shaft and this relation of the shaft and wheel will be maintained until the wheel is again locked and the shaft released by the subsequent depression of the key. Whenever the actuator shaft 27 is released and is rotated by the motor, all of the escapement wheels, with the exception of the one locked by the depression of a key, will rotate with the shaft and maintain their normal relation 110 thereto.

115 *The carriage controlled means for automatically establishing and destroying the operative relation between the keys and the master wheel controlling connections.*—In 120 the absence of mechanism other than that thus far described, the depression of a numeral key to cause the printing of a digit at any point on the work sheet outside of the column to be computed would effect a corresponding operation of the master wheel or actuator 15, although no number wheel of the computing device would be operated, because the computing carriage would not have begun its movement to present a num- 125 130

ber wheel to the actuator. Therefore, the keys would be burdened by the operating or controlling connections of the computing device, and the burden of rewinding the motor would be uselessly imposed upon the carriage during its retraction. To avoid these useless movements of the parts, and thus relieve the keys and carriage of unnecessary burdens, I so arrange the mechanism that the numeral keys will be normally wholly out of coöperative relation with the computing mechanism or its actuator, and provide carriage controlled means for operatively connecting the keys with the actuator when the carriage arrives in position to permit the printing of a digit in the column to be computed, and for automatically moving an element of said connection to an inoperative position to permit the keys to be operated independently of the actuator when depressed to cause the printing of digits outside of the column. To this end the shaft 50 is mounted to rock, as heretofore stated, this movement being utilized to swing the arms 51 into or out of coöperative relation with the key levers 4. Normally, the rock shaft 50 and the arms 51 are disposed in the inoperative position shown in Figs. 5 and 14, being yieldingly retained by a spring detent 62 engaging a notch 63 in the rock shaft 50, Fig. 16. To the right hand end of the shaft 50, Fig. 14, is secured an arm 64 to the extremity of which is attached the lower end of a vertically disposed connecting rod or link 65, attached at its upper extremity to the depending arm 66 of a cam lever 67 fulcrumed as indicated at 68 and having a crescent shaped portion the ends of which constitute a pair of triggers 69 and 70. The trigger 69 normally extends into the path of movement of a trip 71 adjustable on a bar 72 disposed lengthwise of and movable with the typewriter carriage, Figs. 1, 2, 4 and 14. The trip 71 is adjusted along the bar 72 and is secured by a set screw 73 in proper position to engage the trigger 69 in time to trip the latter and pass beyond the same as the carriage moves into position to permit the printing of a digit in the highest denominational position in the column. Obviously, this action of the trip 71 upon the lever 67 is that of a cam. The pin is cylindrical or round in form, and therefore the active surface of the pin which is substantially one-fourth of its circumference, constitutes in effect an inclined surface or cam, it being noted that the cord of the arc of this effective surface of the pin is disposed at an angle of forty-five degrees to the horizontal plane, in which the carriage moves. Thus the trip and the trigger or the cam and the lever, each presents an inclined face to the other, and the movement of these faces along one another 65 by reason of the carriage movement, de-

presses the trigger. When the trigger 69 is thus swung down, the arm 66 of the lever 67 is elevated, thus elevating the arm 64 through the medium of the connecting rod 65 and rocking the shaft 50 to present the arms 51 in the substantially vertical operative position shown in Figs. 6, 7, 15 and 19, the shaft 50 being retained in this position by the detent 62 which engages a second notch 63' in the shaft 50. When the arms 51 are in their normal positions, shown in Figs. 5 and 14, the depression of the numeral keys will not move the bail 48 to release the master wheel or actuator 15. In fact, the keys will be entirely disconnected from both the computing device and its actuator and from the mechanism whereby the operations of the actuator are placed under the control of the keys, but when the carriage has effected the operation of the trigger 69 in the manner described and thus raised the arms 51 to their operative positions, the depression of a key lever will effect the depression of the bail and thus release the actuator to permit the operation of that number wheel which corresponds in denominational position to the digit printed, a number of increments corresponding to the value of such digit.

By reference to Fig. 14, it will be seen that when the trigger 69 is located in the path of the trip 71, the trigger 70 is in a depressed position removed from such path. When, however, the trigger 69 is swung down by the trip, the trigger 70 will be swung up above the trip, Fig. 15, so that when the typewriter carriage is retracted to begin a new line of writing, the trip 71 will engage the trigger 70 and shift the lever 67 back to its normal position. The arms 51 are thus restored to their normal or inoperative positions, and the trip 69 is again presented in the path of trip 71 to be operated, as before described, to coöperatively connect the keys with the actuator at the proper time during the next advance of the carriage.

Attention is now directed to the fact that the movement of the typewriter carriage in the direction of letter spacing automatically effects the relative lateral movement of the number wheels and their actuator to establish their coöperative relation and to change the denominational relation of the actuator with respect to the computing device, and that such movement of the carriage also serves to automatically establish an operative connection between the numeral keys of the typewriter and the actuator to place the latter under the control of the keys during that portion only of the carriage travel which serves to permit digits to be printed in the column to be computed. Attention is also directed to the fact that the retraction of the carriage automatically performs

three distinct functions with respect to the computing mechanism: first, it operates the trip 70 to automatically disconnect the keys from the computing device and the actuator; second, it retracts the computing carriage to dispose the computing device proper in its normal inoperative position, and third, it restores or rewinds the motor, the order of performance being immaterial.

10 Each numeral wheel, except the wheel of highest order, is equipped on the left hand side face thereof with three small segmental trip levers 74, see Fig. 18, fulcrumed intermediate of their ends and associated each 15 with a stop pin 75 which limits the swinging movement of the lever in one direction. The trip levers 74 coöperate with cam lugs or projections 76 extending from the peripheries of a series of resetting cams or disks 20 77, mounted on the number wheel shaft 7 and alternating with the number wheels, Fig. 20. Thus one of these disks 77 is appropriated to each wheel, except the wheel of highest order, and is equipped with three 25 of the projections 76 each of which coöperates with a trip lever 74 in the wheel resetting operation, to be presently described.

The wheel in engagement with the actuator will of course be locked by the latter 30 and it remains to be seen how those wheels located to the right of the actuator are locked.

Mounted to swing from the bar 10 is a number wheel locking bail 100 which extends 35 entirely across the casing 6, as shown in Fig. 17, and which is provided with a locking flange 101 which extends from the right hand end of the bail to a point sufficiently near the plane of the actuator to 40 enable the bail to engage and lock the wheels which may be located to the right of the actuator, but no others. The flange 101 of the locking bail 100 extends between the teeth of the wheels engaged by it, thus serving 45 to accurately align the teeth of the wheels and to lock the same against accidental movement in either direction.

When the computing carriage moves to the left from its normal inoperative position, the successive number wheels move out 50 of engagement with the locking bail and into engagement with the actuator 15.

The means for resetting the number wheels to zero.—Having described the entire 55 mechanism which is necessary for the printing of a column of numbers and the mechanical computation of the column total, I will

now proceed to describe the mechanism whereby the number wheels are reset to zero.

60 Mounted upon the right hand end of the number wheel shaft 7 is a locking wheel 102, Figs. 17, 19 and 29, engaged by the locking bail 100 to securely lock the shaft 7 and the cams 77 against rotary movement. This 65 wheel 102 is provided with one or more,

preferably three, arcuate slots 103 concentric with the shaft 7 and disposed, when the computing carriage is moved to the extreme right hand side of the casing 6, to be engaged by one or more lugs 104 projecting 70 from an annular number wheel resetting member 105. The member 105 is retained against the right hand wall of the casing 6 by screws 106 extended through arcuate slots 107 in the member 105, as shown in 75 Fig. 19. Projecting forwardly from the member 105 is a wheel resetting arm or handle 108 below which the member 105 is formed with an unlocking cam 109 arranged to engage the locking bail 100 and to move 80 the same back to an inoperative position, as shown in Fig. 27; when the arm 108 is swung up. When it is desired to reset the number wheels to zero, the arm 108 is elevated to rotate the resetting member 105. 85 The first part of this movement causes the unlocking cam 109 to throw back the bail 100, the lugs 104 on the resetting member meanwhile traversing the slots 103 in the wheel 102. When the lugs 104 reach the 90 ends of the slots 103, a positive connection will be established between the resetting member and the wheel, and continued movement of the former will therefore cause the wheel 102, the number wheel shaft 7, and 95 the resetting cams 77 to rotate in the direction of the arrow in Fig. 27. This movement of the cams 77 will cause the lugs 76 thereon to engage the trip levers 74 in the manner shown in Fig. 26, thus establishing 100 a positive connection between the cams 77 and the number wheels, since the trip levers will be prevented by the pins 75 from moving out of engagement with the lugs 76. Continued movement of the resetting member 105 in the same direction will thus cause the number wheels to rotate with the shaft until said wheels have reached the zero position, it being evident that when the shaft 7 has been given one-third of a complete 110 rotation, all of the number wheels will necessarily be in position to exhibit "0" before the sight opening. The number wheels having been reset, the resetting arm 108 is 115 swung back to its normal position, thus restoring the shaft 7, the cams 77, and the wheel 102 to their normal positions and withdrawing the unlocking cam 109 from engagement with the locking bail 100 and thus permitting said bail to be restored to 120 its normal or locking position by a spring 110.

In Fig. 5^a is shown a modified form of the escapement wheel locking member 59. In the preferred form, as shown in Fig. 5, 125 the locking member is in the form of an arm secured to the key lever, as already described, but in the modification shown in Fig. 5^a, the locking members 59' are in the form of first-class levers fulcrumed upon a 130

common shaft 59^a extending across the typewriter frame below the key levers, each having its rear end bifurcated and formed with lateral projections 59^b and 59^c engaging the upper and lower edges of a numeral key lever. The front end of each member 59^d is provided with a beak 59^d which is urged upwardly into engagement with the adjacent escapement wheel when the rear end of the member is depressed by the downward movement of the key lever.

It is thought that from the foregoing, the construction and operation of my invention will be clearly comprehended. It should be distinctly understood, however, that I reserve the right to effect such changes, modifications and variations of the illustrated structure as may come fairly within the scope of the protection prayed.

20 What I claim is:—

1. In a computing mechanism, a series of denominational members, a power operated master actuator therefor, and actuator controlling mechanism including a series of keys and a series of rotary escapement elements arranged to be released and arrested upon the depression of a key.

2. In a computing mechanism, a series of denominational members, a power operated master actuator therefor, and actuator controlling mechanism including a rotary member and a key, a series of arresting devices normally movable with said rotary member, and means operative upon the depression of the key to hold one of said arresting devices stationary and to release the rotary member.

3. In a computing mechanism, the combination with a series of denominational members and a motor operated master actuator, therefor, of controlling mechanism for said actuator including a pair of relatively movable stops one of which is movable with the actuator, a key, and means operated thereby for holding the other stop in position to arrest the movement of the stop which moves with the actuator.

4. In a computing mechanism, the combination with a series of denominational members and a motor operated master actuator therefor, of controlling mechanism for said actuator including a rotary member movable with the actuator, a series of stops movable with the rotary member, a second series of stops co-operating with the stops first named, a series of keys, and key-operated means for retaining the stops of the second series in their effective positions.

5. In a computing mechanism, the combination with a series of denominational members and a motor operated master actuator therefor, of controlling means for said actuator including a rotary shaft, a series of stops carried thereby, a second series of stops constituting arresting devices

for the stops of the first named series, a series of keys, means operated by the keys for retaining the second series of stops in their arresting positions, and a key-operated locking device for the actuator.

6. In a computing mechanism, the combination with a series of denominational members and a master actuator therefor, of controlling means for the actuator including a rotary shaft, a series of stops fixed to the shaft, a second series of stops rotatable with the shaft, the stops of the second series being paired with the stops of the first named series and each pair of stops being separated by a different interval, a series of keys, and means operated by each key for retaining a stop of the second series in fixed position to be engaged by the adjacent stop of the other series for the purpose of arresting the rotary movement of the shaft.

7. In a computing mechanism, the combination with a series of denominational members and a master actuator therefor, of actuator controlling means including a rotary shaft, a series of stops fixed thereon, a second series of stops mounted on the shaft and independently movable around the same, the stops of the two series being paired and each pair of stops being separated by a different interval, key-operated means for retaining a stop of the second series stationary to be engaged by the adjacent stop of the other series after a given rotary movement of the shaft, and means for moving the stops of the second series relative to the shaft for the purpose of restoring them to normal position after the shaft has been arrested.

8. In a computing mechanism, the combination with a series of denominational members and a motor operated master actuator therefor, of actuator controlling mechanism including a series of keys, a shaft, two series of paired stops fixed on the shaft, a series of relatively movable arresting stops each disposed between a pair of fixed stops on the shaft, key-operated means for holding one of the arresting stops stationary when a key is depressed, and means operative upon the release of said arresting stop for advancing the same relative to the shaft.

9. In a computing mechanism, the combination with a series of denominational members and a master actuator therefor, of controlling means for said actuator including a series of keys, a shaft provided with stops, and a series of wheels movably mounted on the shaft and provided with stops co-operating with the stops first named, and key-operated means for retaining the desired wheel in fixed position.

10. In a computing mechanism, the combination with a series of denominational members and a master actuator therefor, of controlling means for said actuator includ-

- ing a series of keys, a shaft, and variable stop mechanism mounted on the shaft, said variable stop mechanism comprising a series of stops rigid with the shaft, a series of escapement wheels each provided with a stop arranged to coöperate with one of the stops first named, and mechanism for holding one of the wheels stationary when one of the keys is depressed.
11. In a computing mechanism, the combination with a series of denominational members and a master actuator therefor, of actuator controlling means including a rotary shaft, variable stop mechanism including coöperating stops mounted on the shaft, a series of keys coöperating with the variable stop mechanism to determine the degree of movement of the shaft, and locking means for the actuator arranged for release by either of said keys.
12. In a computing mechanism, the combination with a series of denominational members and a motor operated master actuator therefor, of actuator controlling means, including a shaft, a series of toothed wheels loosely mounted thereon, coöperating stops carried by the shaft and wheels, a series of keys, and a series of holding arms operated by the keys to engage the wheels and hold the same during a partial rotation of the shaft.
13. In a computing mechanism, the combination with a series of denominational members and a motor operated master actuator therefor, of actuator controlling means including a series of keys, a shaft, a series of wheels mounted on the shaft and having limited independent rotary movement, co-operating stops carried by the shaft and wheels respectively, reactive means resisting rearward rotation of the wheels from their normal positions, and means operative to hold one of the wheels stationary when one of the keys is depressed.
14. In a computing mechanism, the combination with a series of denominational members and a motor operated master actuator therefor, of actuator controlling means including a series of keys, a rotary shaft, a series of recessed collars fixed on the shaft, the recesses in the several collars varying in size, a series of peripherally toothed wheels rotatably mounted on the shaft and each provided with a lug extended into the recess of one of the collars, springs constantly urging the wheels in one direction, a series of holding arms each operatively related to a key and arranged to engage the toothed periphery of one of the wheels, a locking device for the master actuator, and key-operated means for operating the locking device to release the actuator.
15. The combination with a computing mechanism and a driving motor therefor, of controlling mechanism including a shaft, a wheel fixed to the shaft and operatively related to the motor, a plurality of variable escape wheels on said shaft, a series of keys, holding devices arranged to be operated by the keys to engage the escape wheels, and a key-operated holding device for the wheel first named.
16. The combination with a computing mechanism, of a driving motor therefor, escapement mechanism controlling the operation of the motor and including a shaft, a plurality of toothed wheels loose on the shaft, coöperating stops carried by the shafts and wheels respectively, said stops having varying relation to permit the wheels to move in varying degree independently of the shaft, and keys controlling the escapement mechanism.
17. The combination with a motor driven computing mechanism, of controlling mechanism therefor including a shaft, a series of wheels mounted thereon and each having a different degree of independent rotary movement, springs for normally holding the wheels at one limit of their independent movement, and keys controlling the wheels.
18. In a computing mechanism, the combination with a series of denominational members and a motor operated master actuator therefor, of actuator controlling mechanism including a plurality of escapement wheels, and keys operatively related to said wheels.
19. In a computing mechanism, the combination with a series of denominational members, of a master actuator therefor, an actuator controlling mechanism including a shaft and a series of wheels constituting elements of an escapement mechanism, and a series of keys each arranged to cause one escapement element to be held stationary during the movement of another.
20. In a computing mechanism, the combination with a series of denominational members and a motor operated actuator therefor, of keys controlling the denominational relation of the denominational members and actuator, and mechanism controlling the operating movement of the actuator, said mechanism including a shaft movable with the actuator, a series of arresting mechanisms distributed along the shaft, said mechanisms being normally ineffective to arrest the shaft but arranged when effective to arrest the shaft after limited rotary movement thereof, and a series of devices each operated by one of the keys to render one of the arresting mechanisms effective.
21. In a computing mechanism, the combination with a series of denominational members and a master actuator therefor, of a series of keys controlling the denominational relation of the denominational members and the actuator, means controlling the operating movement of the actuator, said means in-

cluding a key-operated locking device for the actuator, a shaft, a series of stops fixed to the shaft, a series of arresting stops co-operating with the stops first named but having different degrees of movement independently of the shaft, such independent movement corresponding in degree to the value of the respective keys, and means operated by each key to retain an arresting stop in position to arrest the shaft after the latter has moved a distance corresponding to the value of the key operated.

22. The combination with a computing device; of a typewriting machine including a traveling carriage, printing mechanism and operating keys, an operating connection between the keys and the computing device, and a cam lever extended through the top of the carriage and arranged to disconnect the operating connections from the keys.

23. The combination with a typewriter, of a computing device including a series of denominational members, a master actuator for the computing device, a motor for operating the actuator, means for effecting relative movement of the computing device and its actuator to change the denominational relation thereof, and means brought into action by the movement of the typewriter carriage to establish a co-operative relation between the numeral keys of the typewriter and the actuator.

24. The combination with a typewriter, of a computing device including a series of denominational members, a master actuator therefor, a driving motor for the actuator, differential stop mechanism controlled by the numeral keys of the typewriter to arrest the actuator after predetermined movement thereof, a locking device for the actuator normally disconnected from the numeral keys of the typewriter, and means for automatically establishing a co-operative relation between said numeral keys and the locking device.

25. The combination with a typewriter, of a computing device including a series of denominational members, a master actuator therefor, a driving motor for the actuator, differential stop mechanism controlled by the numeral keys of the typewriter to arrest the actuator after predetermined movement thereof, and a locking device for the actuator normally disconnected from the numeral keys of the typewriter, and means adjustable on the typewriter and arranged to cause a co-operative relation to be automatically established between the numeral keys of the typewriter and the locking device at a predetermined point in the movement of the typewriter carriage.

26. The combination with a typewriter, of a computing device including a series of denominational members, a master actuator for the computing device, a detent for the

actuator, and means for effecting the establishment of a co-operative relation between said detent and the numeral keys of the typewriter, said means including co-operative devices mounted on the typewriter frame and carriage respectively.

27. The combination with a typewriter, of a computing device including a series of denominational members, a master actuator for the computing device, a detent for the actuator, and means for effecting the establishment of a co-operative relation between said detent and the numeral keys of the typewriter, said means including co-operative devices mounted on the typewriter frame and carriage respectively, and one of said devices being adjustable to determine that point in the travel of the carriage at which the co-operative relation between the numeral keys and the detent will be established.

28. The combination with a typewriter, of a computing device, and means for automatically effecting a co-operative relation between the keys and the computing device, said means including a trigger and a co-operating trip, said trigger being movably mounted on the machine frame and said trip being adjustably mounted on the typewriter carriage and arranged to move the trigger out of the path of said trip.

29. The combination with a typewriter, of a computing device, and means for automatically establishing a co-operative relation between the computing device and the numeral keys of the typewriter, said means including a member disposed adjacent to but normally out of operative relation with the key levers of the typewriter, a trigger operatively related to said member, and means presented to the trigger by the relative movement of the typewriter frame and carriage to operate said trigger and move the member into co-operative relation with the key levers.

30. The combination with a typewriter, of a computing device, an actuator therefor, a detent for the actuator, a swinging member disposed for operation by the numeral key levers of the typewriter and arranged to move the detent, and means operated by the relative movement of the machine frame and carriage of the typewriter for establishing a co-operative relation between the swinging member and the key levers.

31. The combination with a typewriter, of a computing device, an actuator therefor, a detent for the actuator, a swinging bail connected to the detent to move the same, and a series of arms or projections carried by the bail and movable into and out of co-operative relation with the numeral key levers of the typewriter.

32. The combination with a typewriter, of a computing device including a series of

denominational members, a master actuator therefor, a driving motor for the actuator, a detent normally holding the actuator against movement, differential stop mechanism for arresting the actuator after predetermined movement thereof, and means operated by the movement of the typewriter carriage for establishing a coöperative relation between the detent and the numeral keys of the typewriter.

33. The combination with a computing device including a series of denominational members, a master actuator therefor, a driving motor for the actuator, a series of stop devices each adapted to arrest the actuator after the latter has moved a distance corresponding to the value of one of the numeral keys of the typewriter, a detent normally holding the actuator against movement, and means for automatically establishing a coöperative relation between the numeral keys of the typewriter and the detent at any one of several points in the travel of the typewriter carriage.

34. The combination with a computing device including a series of denominational members, a master actuator therefor, a driving motor for the actuator, a series of stop devices each adapted to arrest the actuator after the latter has moved a distance corresponding to the value of one of the numeral keys of the typewriter, a detent normally holding the actuator against movement, and means for automatically establishing a coöperative relation between the detent and the numeral keys of the typewriter, said means including a device adjustable on the typewriter carriage.

35. The combination with a computing device including a series of denominational members, a master actuator therefor, a driving motor for the actuator, a series of stop devices each adapted to arrest the actuator after the latter has moved a distance corresponding to the value of one of the numeral keys of the typewriter, a detent normally holding the actuator against movement, and means for establishing a coöperative relation between the detent and the numeral keys of the typewriter, said means including a member connected to the detent and movable into and out of operative relation with a numeral key lever, and means operated by the movement of the typewriter carriage for moving said member.

36. The combination with a computing device including a series of denominational members, a master actuator therefor, a driving motor for the actuator, a series of stop devices each adapted to arrest the actuator after the latter has moved a distance corresponding to the value of one of the numeral keys of the typewriter, a detent normally holding the actuator against movement, and

means for establishing a coöperative relation between the detent and the numeral keys of the typewriter, said means including a bail connected to the detent, a rocking member carried by the bail, and means for 70 rocking said member into and out of coöperative relation with the numeral key levers of the typewriter.

37. The combination with a computing device including a series of denominational members, a master actuator therefor, a driving motor for the actuator, a series of stop devices each adapted to arrest the actuator after the latter has moved a distance corresponding to the value of one of the numeral keys of the typewriter, a detent normally holding the actuator against movement, and means for establishing a coöperative relation between the detent and the numeral keys of the typewriter, said means including 80 a bail, a rocking member carried by the bail, a pivoted trigger connected to the member to rock the same, and a trip, the trigger and trip being brought into coöperative relation by the movement of the 85 typewriter carriage.

38. In a computing mechanism, the combination with a series of denominational members, a motor driven master actuator therefor, a detent for the actuator, stop mechanism for arresting the actuator, a series of keys, a reciprocatory carriage, and means operated by the movement of the carriage in one direction for establishing a coöperative relation between the keys and the 100 detent, said means being operated by the movement of the carriage in the opposite direction to render the keys and the actuator independent of each other.

39. The combination with a typewriting machine, of a computing device including a series of denominational members, a motor operated actuator therefor, stop mechanism for arresting the actuator, a detent normally holding the actuator against movement, and means operated by the forward movement of the typewriter carriage for establishing a coöperative relation between the detent and the numeral keys of the typewriter, said means being operated by the retractile movement of the carriage to render the detent and the numeral keys independent of each other.

40. The combination with a computing device and a series of keys, of a traveling carriage, a trip movable therewith, a plurality of triggers disposed for operation by the trip, and means operated by the triggers for establishing a coöperative relation between the keys and the computing device 120 and for rendering the keys and computing device independent of each other.

41. The combination with a typewriter, of a computing device, a plurality of triggers, a trip movable with the typewriter 125

carriage to operate the triggers, and means operated by the triggers for establishing a coöperative relation between the computing device and the numeral keys of the typewriter and for rendering the keys and computing device independent of each other.

42. In a computing mechanism, the combination with a series of denominational members and a motor operated master actuator therefor, of stop mechanism for arresting the actuator, a detent normally holding the actuator against movement, a series of keys, a plurality of triggers, a movable trip disposed to operate the triggers, and means operated by the triggers for establishing a coöperative relation between the keys and the detent and for rendering the keys and detent independent of each other.

43. The combination with a typewriter, of a computing device including a series of denominational members, a motor driven master actuator therefor, stop mechanism for arresting the actuator, a detent normally holding the actuator against movement, a pair of triggers, means controlled by said triggers for establishing a coöperative relation between the numeral keys of the typewriter and the detent and for rendering the keys and detent independent of each other, and a trip for operating the triggers.

44. The combination with a typewriting machine, of a computing device, and means controlling the coöperative relation between the numeral keys of the typewriter and the computing device, said means including a controlling lever formed with a plurality of triggers operated through the movement of the typewriter carriage.

45. The combination with a typewriting machine, of a computing device, and means controlling the coöperative relation between the numeral keys of the typewriter and the computing device, said means including a controlling lever formed with a plurality of triggers and a coöperating trip adjustably mounted on the carriage of the typewriter.

46. The combination with a typewriter, of a computing device including a series of denominational members, a motor driven master actuator therefor, stop mechanism for arresting the actuator, a detent normally holding the actuator against movement, and means controlling the coöperative relation between the said detent and the numeral keys of the typewriter, said means including a controlling lever formed with a plurality of triggers and a trip mounted on the typewriter carriage and arranged to operate said triggers.

47. In a computing mechanism, the combination with a series of denominational members, of operating mechanism therefor including a motor, and motor restoring means including an arm having a movement

proportionate to the power expended by the motor and means for returning the arm to normal position.

48. In a computing mechanism, the combination with a series of denominational members and a master actuator therefor, of a motor for the actuator, a motor restoring arm, and a reciprocatory carriage disposed to engage and operate the restoring arm.

49. The combination with a computing device, of an operating motor therefor including a rotary member, a motor restoring arm extending from said member and, movable therewith, and means for operating said arm to restore the rotary motor member to normal position.

50. The combination with a computing device, of operating mechanism therefor including a motor shaft, reactive driving means therefor, an arm extended from the motor shaft, and means for engaging and operating said arm to rotate the motor shaft to its normal position.

51. The combination with a typewriting machine, of a computing device, operating mechanism therefor including a motor shaft, reactive driving mechanism therefor, a motor gear having pawl and ratchet connection with the motor shaft, and means operated by the movement of the typewriter carriage for automatically rotating the motor shaft to restore the power of the motor.

52. The combination with a computing device, of an actuator therefor, a motor shaft geared to the actuator, reactive driving means for the motor shaft, a motor restoring arm movable with the motor shaft, and means for operating the arm to restore the motor shaft to normal position independently of the actuator.

53. The combination with a typewriter, of a computing device, operating mechanism therefor including a motor controlled by the keys of the typewriter, a motor restoring device movable a distance proportionate to the power expended by the motor and disposed in the path of the retractile movement of the typewriter carriage.

54. The combination with a typewriter, of a computing device, a driving motor therefor controlled by the numeral keys of the typewriter, a motor restoring arm mounted to swing as the motor is operated and disposed beyond one end of the typewriter carriage to be engaged thereby and returned to normal position as the carriage is retracted.

55. The combination with a typewriter, of a computing device, a driving motor therefor, means operated by the forward movement of the typewriter carriage for establishing a coöperative relation between the computing device and the numeral keys of the typewriter at any one of several points in the travel of the carriage, and

means operated upon the retraction of the carriage for restoring the expended energy of the motor.

56. The combination with a typewriter, of a computing device, a driving motor therefor, means operated by the typewriter carriage for establishing a coöperative relation between the numeral keys of the typewriter and the computing device during the forward movement of the carriage and for rendering the keys and computing device independent during the retraction of the carriage, and means operated by the typewriter carriage during its retraction to restore the energy expended by the motor.

57. The combination with a typewriter, of a computing device including a series of denominational members, a master actuator for said members, an actuator shaft provided with a series of stops, arresting devices controlled by the numeral keys of the typewriter and coöperating with the stops, a detent for the actuator, a motor for driving the actuator when released, means operated by the carriage for operatively connecting the numeral keys of the typewriter with the detent, and means also operated by the carriage for restoring the energy expended by the motor.

58. The combination with a typewriter, of a computing device, a driving motor for the latter, a plurality of triggers disposed for actuation by the movement of the typewriter carriage, means operated by said triggers and controlling the coöperative relation between the numeral keys of the typewriter and the computing device, and means operated by the typewriter carriage for restoring the energy expended by the motor.

59. The combination with a typewriter, of a computing device, a driving motor therefor, a trigger operable by the forward movement of the typewriter carriage to establish a coöperative relation between the numeral keys of the typewriter and the computing device, a second trigger operable by the retractile movement of the typewriter carriage to render the numeral keys independent of the computing device, and means also operated by the retractile movement of the carriage for restoring the energy expended by the motor.

60. The combination with a typewriter, of a computing device including a series of denominational members, a master actuator therefor, a driving motor for the actuator, a trigger operable by the forward movement of the typewriter carriage to establish a coöperative relation between the numeral keys of the typewriter and the actuator, a second trigger operated by the retraction of the typewriter carriage to render the numeral keys independent of the actuator, and means operated by the carriage for restoring the energy expended by the motor.

61. The combination with a typewriter, of a computing device and an operating motor therefor, both mounted beyond one end of the typewriter, and mechanism for operatively connecting the numeral keys of the typewriter with the computing device.

62. The combination with a typewriter, of a computing device and an operating motor therefor both mounted on the main frame of the typewriter beyond one end thereof, an actuator for the computing device arranged to be driven by the motor, an actuator shaft extended across the series of key levers of the typewriter, stop mechanism controlled by the key levers and arranged to arrest the rotary movement of the actuator shaft, and a detent for the actuator arranged to be moved by the key levers to release the actuator.

63. The combination with a typewriter, of two elements, to-wit, a computing device and an actuator, relatively movable to change their denominational relation, and means for effecting such relative movement, said means including a rock shaft having two arms one of which is connected to one of said elements to move the same, and a pair of spaced devices movable with the typewriter carriage to engage and operate the other arm of the rock shaft.

64. The combination with a typewriter, of two elements, to-wit, a computing device and an actuator relatively movable to change their denominational relation, and means for effecting such relative movement, said means including a rock shaft having two arms one of which is connected to one of said elements to move the same, and a pair of spaced devices movable with the typewriter carriage to engage and operate the other arm of the rock shaft, one of said devices being independently adjustable.

65. The combination with a typewriting machine, of a computing device, an actuator therefor, the computing device and actuator being relatively movable to change their denominational relation, means operated by the typewriter carriage for effecting such relative movement, and means operated by the carriage for establishing a coöperative relation between the numeral keys of the typewriter and the actuator.

66. The combination with a typewriting machine, of a computing device and an actuator relatively movable to change their denominational relation, adjustable means operated by the typewriter carriage for inaugurating such relative movement at the desired point in the travel of the carriage, and adjustable means operated by the typewriter carriage for establishing a coöperative relation between the numeral keys of the typewriter and the actuator at the proper point in the carriage travel.

67. The combination with a typewriter, of

5 a computing device and an actuator having relative movement to change their denominational relation, means operated by the typewriter carriage for effecting such relative movement, a motor for driving the actuator, and means operated by the typewriter carriage to automatically effect a co-operative relation between the actuator and the numeral keys of the typewriter.

10 68. The combination with a typewriter, of a computing device and an actuator relatively movable to change their denominational relation, means operated by the typewriter carriage to effect such relative movement, a motor for driving the actuator, a detent normally holding the actuator against movement, means operated by the carriage to automatically establish a co-operative relation between the numeral keys of the typewriter and the detent, and stop mechanism for arresting the actuator when the latter has moved a distance proportionate to the value of the key depressed.

15 69. The combination with a typewriter, of a computing device and an actuator relatively movable to change their denominational relation, means operative during both the forward and retractile movements of the typewriter carriage to effect relative movement of the computing device and actuator, a motor for driving the actuator, motor restoring mechanism operated by the retractile movement of the carriage to restore the power expended by the motor, means operative during the forward movement of the carriage to establish a co-operative relation between the actuator and the numeral keys of the typewriter, said means being operated by the retractile movement of the typewriter carriage to render the numeral keys independent of the actuator.

20 70. The combination with a shaft, of a series of denominational members loosely mounted on the shaft and arranged to slide longitudinally thereof, means for operatively connecting the shaft to the denominational members to effect the resetting of the latter by the rotation of the shaft, a resetting device normally disconnected from the shaft, and means for connecting the resetting device with the shaft when the denominational members occupy a given position on the shaft.

25 71. The combination with a movable computing carriage, a series of denominational members mounted therein, a resetting member mounted independently of the carriage, and means for causing the movement of the carriage to operatively connect the resetting member with the denominational members.

30 72. The combination with a computing carriage, of a shaft extended therethrough, a series of denominational members mounted on the shaft and movable with the computing carriage, a locking wheel also mounted

35 on the shaft and movable with the carriage, a locking device normally engaging the locking wheel to hold the shaft against rotation, a resetting member normally disconnected from the locking wheel, but brought into co-operative relation therewith by the movement of the computing carriage, and means operated by said resetting member for unlocking the locking wheel and for subsequently rotating the same to effect the resetting of the denominational members.

40 73. In a calculating machine, the combination of a receiving mechanism; operating means therefor, one adapted to travel relatively to the other and adapted to make so positive geared connection therewith for a limited portion of the travel of the traveling part, said operating means being normally non-operative; and a cam device whereby the operator may predetermine whether or not the connection shall be established between the receiving mechanism and operating means within the possible field of operation, said cam device including two co-operating pieces, one of which travels in unison with the traveling part of the machine, and one of said two co-operating pieces being adapted to contact the other for a distance terminating short of the termination of travel of the traveling part of the machine, and one of said co-operating pieces being a cam adapted to move its co-operating piece in a direction non-coincident with the line of travel, and one of said co-operating pieces being capable of being set in two positions in only one of which it may come into contact with its co-operating piece.

45 74. In combination, a receiving mechanism and operating means therefor, one traveling relatively to the other, and a selection device by means of which the operator may predetermine whether the connection between the receiving mechanism and operating means shall be established, said selection device including a plurality of parts, one traveling and the other stationary; one of the parts when set to engage the other being effective thereon for a limited distance to establish the connection between the receiving mechanism and the operating means, but being ineffective thereon during further movement in the same direction.

50 75. The combination with a typewriting machine, including printing mechanism, a frame, and a traveling carriage, of a cam, and a lever presented in operative relation by the movement of the carriage, a computing device, and means controlled by the lever for rendering the computing device operative.

55 76. In a computing mechanism, a series of denominational members, a power operated master actuator therefor, an actuator controlling mechanism including a series of keys and a series of escapement elements ar-

ranged to be released and arrested upon the actuation of a key in said series of keys.

77. In a computing mechanism, a movable carriage, a series of denominational members, a power operated master actuator therefor, an actuator controlling mechanism including a series of keys, a series of escapement elements arranged to be released and arrested upon the actuation of a key in said series, and means controlled by said keys for causing said denominational members to be successively connected with said master actuator.

78. In a computing mechanism, a series of denominational members, a power operated

master actuator therefor, an actuator controlling mechanism including a series of keys and a series of escapement elements arranged to be released and arrested upon the actuation of a key in said series, and means for determining when said keys may become operative to control said escapement elements.

In testimony whereof I have hereunto set my hand in the presence of two subscribing witnesses.

JAMES DENNY DAUGHERTY.

Witnesses:

JOHN HENRY PAINTER,
R. W. MOORHEAD.
